SHACKLE SEAL

Winfred M. Brooks, West Orange, N. J., assignor
to E. J. Brooks Company, Newark, N. J., a
corporation of New Jersey

Application January 27, 1938, Serial No. 187,108

2 Claims. (Cl. 292—309)

This invention relates to shackle seals and has more particularly reference to bag seals such as are employed in sealing coin bags used by banks and other financial institutions.

The main objects and features of the invention are to prevent tampering with the cord shackle by unauthorized persons or accidental severing thereof, without preventing a person in authority from readily severing the cord; to relieve the pull of the cord on the lead seal; and to prevent over-pulling on the cord and the consequent possibility of snapping it off when applying the seal.

In the accompanying drawing the invention is shown in several concrete and preferred forms in which

Fig. 1 is a view, partly in elevation and partly in section, of a device embodying one form of the invention and showing the position the parts may occupy before applying the seal to the bag;

Fig. 2 is a fragmentary view of the top of a coin bag showing the seal applied;

Fig. 3 is a horizontal sectional view substantially on the plane of line 3—3 of Fig. 2;

Fig. 4 is a view similar to Fig. 1 showing a modified form of the invention; and

Figs. 5 and 6 are views in elevation showing still other forms of the invention.

1 indicates a bag such as is commonly employed for the transport of coins or other objects, and it has long been common practice to seal the mouth of such bags by means of a shackle of cord and a seal of compressible material, the cord being severed when it is desired to open the bag. It will be understood that in sealing the bag, the loop of the cord shackle is placed around the open end of the bag, the loop is pulled through the seal and the seal is compressed by a suitable tool. In carrying out this operation, the cord is placed under considerable tension and sometimes overpulling takes place thereby snapping off the cord. So also, owing to the tension, considerable strain is imposed upon the lead seal where the cord passes through it and in consequence it has sometimes been found possible for an unauthorized person to pull the cord back through the lead seal to partly open the loop, give access to the contents of the bag and thereafter to pull the loop tight again thus leaving no trace of tampering. Although these and other defects have long been known, no means have heretofore been devised to overcome these objections.

My invention consists in combining with the shackle and seal a flexible member composed of open helices, the details of which combination I shall now proceed to describe. 2 is a seal of com-

pressible material such as lead, and on this seal is anchored a shackle 3 of flexible material such as cord or twine that may be readily severed. This shackle may be anchored in any suitable way in the seal such as by imbedding one end in the lead 5 of the seal and passing the other and free end through an opening in the seal so as to provide a loop to pass around the mouth of the bag. In the present instance the shackle is anchored by providing seal 2 with four openings 4 and threading 10 opposite ends of the shackle first through two openings of the seal and then back through the other two openings of the seal thus forming a loop 15 composed of two strands which strands slide in opposite directions past each other when the loop is tightened. 6 indicates a flexible member composed of open helices to slidably receive the loop and through which the strands are threaded before passing them back through the seal. It will now be understood that the loop is placed around 20 the bag, after which said loop is tightened by pulling on the free ends of the strand and that by this action said member is flexed into a curved form the outer circumference of which is under tension and the inner circumference of which is under compression, the seal acting as an abutment, after 25 which the seal is compressed. The effect is shown in Figs. 2 and 3, and several important results are thereby obtained. In the first place the helices 30 are compressed adjacent the bag and consequently bite into the material of the bag as it were and this lessens the strain of the bag on the cord and of the cord on the interior of the seal, because the cord need not be pulled as tightly to make the helices bite into the material of the bag as would 35 be necessary if the material of the bag is engaged by the cord. Thus there is less tendency for the shackle to work loose; also the presence of the member makes it practically impossible to introduce say a screw driver between the bag and one 40 of the strands of the shackle should an attempt be made to tamper with the seal. At the same time the outer circumference of the helices is expanded thus enabling an authorized person to readily 45 insert a knife between the helices and sever the cord, and to do so without cutting into the bag as the inner circumference of the helices protects it. In addition, when tightening the loop of the shackle, the helical member acts as a cushion that tends to prevent overpulling of the shackle. The 50 helical member also keeps the strands of the shackle from twisting around each other as it preserves a proper side by side relation of said strands and facilitates the sliding movement of said strands past each other. Finally, the helical 55

member protects the shackle from being accidentally cut or injured by reason of careless handling.

The invention is capable of embodiment in other forms than that described in connection with Figs. 1 to 3. In Fig. 4, for instance, the helical member is provided with an extension 7 that permanently attaches said member to the seal. In Fig. 5 the helical member is composed of two parts 8 and 9. It is not necessary that the helical member be initially arranged at one side of the loop; there is a positive advantage in arranging it as shown at 10 in Fig. 6 at the center of the loop because in that position it tends to keep the loop more widely open and thus facilitates the action of placing said loop around the neck of the bag. A great many of these bag seals carry a spike as 11 which pierces the material of the bag and therefore tends to prevent displacement of the seal but, bags of different sizes being used, it sometimes occurs through carelessness that a seal with a long spike as 11 is used on a small bag in which event said spike may emerge on the other side of the bag and may injure the fingers of the operator. It will be seen that, in addition to its many other functions, the helical member will protect the sharp end of the spike.

I claim:

1. The combination of a shackle of flexible material anchored in and threaded through a seal, the loop of which shackle is to be tightened around a member to be sealed by pulling said shackle through the seal; a flexible member composed of open helices surrounding and slidably receiving said shackle; and a seal, in which the shackle is anchored and through which it is slid able to tighten the loop of the shackle around the object to be sealed, said seal acting as an abutment for said member to cause it to be flexed into curved form when the loop of the shackle is tightened.

2. The combination of a shackle of flexible material anchored in and threaded through a seal, the loop of which shackle is to be tightened around a member to be sealed by pulling said shackle through the seal; a flexible member surrounding and slidably receiving said shackle; and a seal, in which the shackle is anchored and through which it is slid able to tighten the loop of the shackle around the object to be sealed, said seal acting as an abutment for said member to cause it to be flexed into curved form when the loop of the shackle is tightened.

WINFRED M. BROOKS.
